UNITED STATES PATENT OFFICE

164,852

HOLY-WATER DISPENSER

Otto S. Gibson, Butte, Mont., assignor of 33/100 to Bruce Albert Rademacher and 33/100 to Martha Davisson Gibson, both of Butte, Mont.

Application April 14, 1950, Serial No. 9,214

Term of patent 14 years

(Cl. D29—23)

To all whom it may concern:

Be it known that I, Otto S. Gibson, a citizen of the United States of America, residing at Butte, in the county of Silver Bow and State of Montana, have invented a new, original, and ornamental Design for a Holy-Water Dispenser, of which the following is a specification, reference being had to the accompanying drawing, forming part thereof.

The characteristic features of the design are shown in full lines.

I claim:

The ornamental design for a holy-water dispenser, as shown and described.

OTTO S. GIBSON.
